KITCHEN SINK AND SINK ASSEMBLY

Harold A. Patton, San Carlos, Calif.

Application May 7, 1946, Serial No. 667,878

7 Claims. (Cl. 4—187)

1

This invention relates in general to a kitchen sink and sink assembly, and more particularly to an assembly of this character wherein an effective and permanent seal is provided between the drain board covering and the sink.

In kitchen sink assemblies, the drain boards are constructed of a hard rigid material or a relatively resilient material. The former includes those made of tile, cement, metal and those which are formed as part of the sink itself. The latter includes those made of wood and those covered with linoleum or a similar covering.

Hard surfaced drain boards have been found unsatisfactory since such a surface results in excessive breakage of china and glassware. Tile and cement drain boards are brittle and easily chipped in normal usage.

Wooden drain boards are unsatisfactory since they warp, crack and absorb moisture, thus becoming sour and impossible to clean properly. Although linoleum-covered drain boards are desirable in that the breakage of china and glassware is minimized, like those of a hard surface and those constructed of wood, they are unsatisfactory in that it has been impossible, heretofore, to effect a permanent water-tight seal between the drain board and the sink. This results in liquids and the particles of food carried by these liquids seeping between the sink and drain board where they cannot be removed.

Normally kitchen sinks are constructed with an outwardly extending peripheral flange which is generally used to suspend the sinks of their cabinets or frameworks. In manufacture, the entire working surface of these sinks, including the flange, is enamel-coated. When the enamel is applied to the sinks, they are subjected to such high temperatures that the flanges are warped and, as a result, their surfaces are rippled and uneven. A permanent water-tight seal must be effected between this uneven surface of the flange and the drain board if the assembly is to be maintained in a sanitary condition. However, such a seal has not been devised since cement seals will not properly adhere to the enameled surfaces, and metal trim seals cannot be molded or bent so as to snugly fit the irregularities of the uneven surface of the flange.

It is the object of this invention to provide a generally improved kitchen sink and drain board assembly wherein a permanent water-tight seal is effected between a resilient drain board covering and a sink having an even and true upper edge.

It is further an object of this invention to pro-

2

vide a kitchen sink assembly comprising a drain board; a sink rigidly affixed to said drain board with the upper edge of its peripheral wall flush with and in extension of the upper surface of said drain board; a trim seal T-shaped in cross-section snugly affixed to said drain board and sink with its leg member overlying the joint between the sink and drain board and the lower portion of its cross member overlapping the upper margin of said peripheral wall; and a drain board covering cemented over the leg of said trim seal and over the drain board with its edge abutting the upper portion of the trim seal.

The invention possesses other advantageous features, some of which with the foregoing will be set forth at length in the following description, where one form of the invention has been selected in the accompanying drawings and forming a part of the present specification is outlined in full. In said drawings one form of the invention is shown, but it is to be understood that it is not limited to such a form since the invention as set forth in the claims may be embodied in other forms.

25 Referring to the drawings:

Fig. 1 is a perspective view of the sink and sink assembly with parts broken away to more clearly show its construction.

Fig. 2 is a sectional view taken on the line 30 2—2 of Fig. 1.

Fig. 3 is a detail of seal between the sink and its associated drain board.

The device as shown in these figures comprises a horizontally disposed sink 1, mounted on a drain board 2 and formed with a substantially vertical and upstanding peripheral wall 3. While the inner surface of the sink 1 may be coated with porcelain, an upper edge 4 of its peripheral wall 3 is uncoated and can be machined so as to have a true and even surface. The drain board 2 is formed with a cut-out section, the periphery of which conforms to the outer surface of the wall 3.

45 Integrally formed with the outer surface of each of the end sections of the peripheral wall 3 is a horizontally disposed flange 5. The flanges 5 are formed with a plurality of longitudinally aligned, threaded holes 6 a spaced distance apart, each of which is suitably threaded to receive a bolt 7.

Affixed to the lower surface of the drain board 2 immediately adjacent to and parallel with each of the flanges 5 is an angle iron 8. The projecting ear of the angle iron 8 is formed with a plurality of laterally disposed slots 9, one being in

register with each of the threaded holes 6 in the flanges 5.

In mounting the sink 1 on the drain board 2, the former is positioned within the cut-out section in the latter so that the upper edge of peripheral wall 3 of the sink 1 is flush with the upper surface of the drain board 2. The sink 1 is then rigidly secured to the drain board by engaging the slots 9 in the angle iron 8 with the bolts 7 and tightening the same. As illustrated in Fig. 2, the slots provided in the angle iron 8 permit the sink to be adjusted during installation in relation to the drain board 2 a sufficient amount so that the upper edge of the peripheral wall 3 can be positioned flush with the upper surface of the drain board 2. When the bolts 7 are tightened, the sink is rigidly secured to the drain board. This rigid connection is of sufficient strength to maintain at all times the relationship of the sink to the drain board 2 so that the seal is never broken by movement of the sink or the drain board 2.

Mounted on the upper surface of the drain board 2 with its lower portion 17 overlapping an upper margin of peripheral wall 3 is a metal trim seal 11, T-shaped in cross-section. As illustrated in Fig. 1, the leg 12 of the trim seal 11 extends outwardly from the sink a sufficient distance to permit its attachment to the drain board 2 by means of screws 13. An upper portion 14 of the trim seal 11 is undercut to receive a drain board covering 15 which is cemented or otherwise fixed in position on top of the leg of the trim seal 11. In order to eliminate any bulging or unevenness in the covering 15, a strip of material 16 of a thickness equal to that of the leg of trim seal 11 is positioned in abutment with the outer end of the leg 12 of the seal 11 extending intermediate the drain board 2 and the covering 15.

It should be noticed that the leg 12 and the upper portion 14 of the seal 11 form an undercut angle in which the edge of the covering 15 can be securely positioned so as to effect a water-tight joint. It should be further noticed that the line of contact between the sink 1 and the drain board 2 is completely covered by the trim seal 11 and the covering 15. As is customary, all contacting parts of the trim seal 11 are coated with a cementing compound 18 to insure water-tight joints.

From the foregoing description, it is apparent that a permanent water-tight seal has been effected between the drain board covering and the upper edge of the sink. If any liquid is to seep between the sink and the drain board covering, it must first travel upwardly between the lower portion 17 of the trim seal and the sink and then travel between the leg 12 of the trim seal and the abutting even upper edge of the sink.

I claim:

1. A device of the character described comprising: a drain board; a sink rigidly affixed to said drain board with the upper edge of its peripheral wall flush with and in extension of the upper surface of said drain board the side walls of said sink being unobstructed from top to bottom; a trim seal T-shaped in cross-section snugly affixed to said drain board and sink with its leg member overlying the joint between the sink and drain board and the lower portion of its cross member overlapping the upper margin of said peripheral wall; and a drain board covering cemented over the leg of said trim seal and over

the drain board with its edge abutting the upper portion of the trim seal.

2. A device of the character described comprising: a drain board; a sink adjustably affixed to said drain board with the upper edge of its peripheral wall flush with and in extension of the upper surface of said drain board the side walls of said sink being unobstructed from top to bottom; a trim seal T-shaped in cross-section snugly affixed to said drain board and sink with its leg member overlying the joint between the sink and drain board and with the lower portion of its cross member overlapping the upper margin of said peripheral wall; and a drain board covering cemented over said drain board and over the leg of said trim seal with its edge abutting the upper portion of the trim seal.

3. An assembly of the character described comprising: a drain board; a sink adjustably affixed to said drain board with the upper edge of its peripheral wall flush with and in extension of the upper surface of said drain board the side walls of said sink being unobstructed from top to bottom; a trim seal T-shaped in cross-section formed with an upper undercut angle, said trim seal being snugly affixed to said drain board and sink with its leg member overlying the joint between the sink and drain board and with the lower portion of its cross member overlapping the upper margin of said peripheral wall; a drain board covering cemented over said drain board and over the leg of said trim seal, with its edge accommodated in said undercut angle.

4. An assembly of the character described comprising: a drain board; a sink having a peripheral wall terminating in a substantially true and even upper edge and having side walls unobstructed from top to bottom; means for adjustably securing said sink to said drain board with said upper edge flush with and in extension of the upper surface of said drain board; a trim seal T-shaped in cross-section formed with an upper undercut angle, said trim seal being cemented to said drain board and sink with its leg member overlying the joint between the sink and drain board and with the lower portion of its cross member overlapping the upper portion margin of said peripheral wall; a drain board covering cemented over said drain board and over the leg of said trim seal with its edge securely positioned in said undercut angle.

5. An assembly of the character described comprising: a drain board; a sink having upstanding side and end walls terminating in a substantially true and even upper edge said side walls being unobstructed from top to bottom; means for adjustably securing said sink to said drain board with said upper edge flush with and in extension of the upper surface of said drain board; a trim seal T-shaped in cross-section formed with an upper undercut angle, said trim seal being snugly affixed to said drain board and sink with its leg member overlying the joint between the sink and drain board and the lower portion of its cross member overlapping the upper margin of said peripheral wall; a filler member substantially of equal thickness to the leg of said trim seal abutting the outer end of said leg and overlying said drain board; a drain board covering cemented over said filler member and over the leg of said trim seal with its edge securely positioned in said undercut angle.

6. An assembly of the character described comprising: a drain board formed with a cut-out section; a sink having upstanding side and end

walls terminating in a substantially true and even upper edge said side walls being unobstructed from top to bottom; means for adjustably affixing said sink to said drain board within said cut-out section with said upper edge of the sink flush with and in extension of the upper surface of said drain board; a trim seal T-shaped in cross-section formed with an upper undercut angle, said trim seal being snugly affixed and cemented to said drain board and sink with its leg member overlying the joint between the sink and drain board and the lower portion of its cross member overlapping the upper margin of the peripheral wall of said sink; a filler member substantially of equal thickness to the leg of said trim seal, abutting the outer end of said leg and overlying said drain board; a drain board covering cemented over said filler member and leg of said trim seal with its edge securely positioned in said undercut angle.

7. An assembly of the character described comprising: a drain board formed with a sink opening; a sink disposed in said sink opening with its upper peripheral edge on a level with and forming a continuation of the upper surface of said drain board, the outer side walls of said sink being straight and unobstructed throughout
